UNITED STATES PATENT OFFICE.

KIRBY FITZPATRICK, OF OKLAHOMA, OKLAHOMA.

AUTOMATIC GUN.

1,161,384.

Specification of Letters Patent. Patented Nov. 23, 1915.

Application filed July 18, 1914. Serial No. 850,690.

To all whom it may concern:

Be it known that I, KIRBY FITZPATRICK, a citizen of the United States of America, residing at Oklahoma city, in the county of Oklahoma and State of Oklahoma, have invented certain new and useful Improvements in Automatic Guns, of which the following is a specification.

This invention relates to a new and useful improvement in fire arms, more especially magazine breech loaders.

The object of the invention is to adapt a rotary breech block to such a type of gun so that the breech block may be used to transfer the cartridges from the magazine of the gun to the barrel and also to eject the empty shells.

The invention consists in the construction hereinafter pointed out and claimed.

20 In the annexed drawings: Figure 1 is a longitudinal section on line 1—1, Fig. 2, through the rear end of a gun containing the invention. Fig. 1^a is an enlarged detail of part of Fig. 1, looking in the direction of the arrow. Fig. 2 is a vertical transverse section on line 2—2, Fig. 1. Fig. 3 is a sectional view, similar to that of Fig. 2, with the position of the breech block changed. Fig. 4 is a perspective view of the breech block. Fig. 5 is a longitudinal section through a portion of the rear end of the gun, showing the breech block in a position different from that shown in Fig. 1. Fig. 6 is a vertical transverse section, similar to 35 that of Figs. 2 and 3, with the position of the breech block still further changed. Fig. 7 is a detail view showing an edge view of the hammer and an end view of the stem of the breech block.

40 In these drawings: The numeral 1 designates a gun having the barrel 2, the magazine 3 and the breech 4. The breech 4 has a chamber 5, with a side opening 6, a hollow space 7 back of the chamber 5, two slots 8 and 9 in the bottom, a notch 10 between these slots, a recess 11 at the top on the inside and a recess 12 in the middle opening into the front end of the chamber 5. The slot 8 is at the rear end 13 of the magazine 3 and is 45 made with a lengthwise portion 14 and a crosswise portion 15, where the magazine 3 joins the chamber 5, and the slot 8 opens into the interior of the magazine 3. In the chamber 5 is placed the breech block 16. 50 This is shown in perspective in Fig. 4. It is substantially the segment of a cylinder,

having a rounded portion 17 and a flattened portion 18. The rounded portion 17 at one side is shorter forming a recess 19 at the end 20 of the breech block. In this breech block is made a bore 21 running nearly through the breech block, having the front end 22 open and the rear end 23 closed. In the flattened portion 18 there is made a concave recess 24 extending almost the entire 60 length of the breech block having an open end 25 and closed at the end 26. At its front end 20, the breech block 16 has at the center of this end 20 a pintle 27 fitting the recess 12 of the breech. Extending centrally 65 through the breech block 16 is a bore 28 closed at the pintle end and having the opening 29 at the rear end 30 of the breech block. Opening from the bore 28 into the bore 21 is a slot 31 and another slot 32 opens from 70 the bore 28 into the recess 24. The slot 31 and the slot 32 are the same length but the slot 31 extends farther toward the end 30 of the breech block 16. In bore 21 is placed a plunger 33 having a flat head 34 toward 75 the front end 22 of the bore and the cup 35 extending rearwardly from this head 34. In the cup 35 is placed a spiral spring 36 which bears between the flat head 34 and the closed end 23 of the bore when the plunger 80 33 is at that end of the bore. Secured to the outside of the flat head 34 of the plunger 33 is a lug 37 of an extractor 38, the lug extending through the slot 31 and the body 39 of the extractor snugly fitting the central 85 bore 28. The operative finger 40 of the extractor extends through the slot 32 and protrudes into the concave 24. In the solid portion of the breech block near the center 90 of the block there is a passage 41 parallel with the axis of the block and also another oblique passage 42 running from the edge of the end 30 of the breech block 16 to about the center of the end 43 at recess 19. At the front end of the passage 41 there is an enlargement 44 of the passage and another 95 enlargement 45 at the front end of the passage 42. At the front end of the enlargement 44 is a nut 46 with a smooth hole 48 therein and at the front end of the enlargement 45 is a nut 47 with a smooth hole 49 therein. In the passage 41 is placed a recoil bolt 50 having a collar 51 in the enlargement 44 and a flat end 52 protruding through the hole 48 of the nut 46. Around 100 the recoil bolt 50 in the enlargement 44 are the springs 53 and 54, one on each side of

105

110

the collar 51. In the passage 42 is a firing pin 55 having a collar 56 in the enlargement 45 and a pointed end 57 protruding through the hole 49 of the nut 47. Around the firing pin 55 in the enlargement 45 are the springs 58 and 59, one on each side of the collar 57. At the other end 30, the breech block 16 has a shallow radial kerf 60, made in its outer face in line with the ends of the 10 passages 41 and 42. This kerf has straight sides 61 and 62 and a curved end 63. In the curved surface of the breech block 16 there is a channel 64 running partially around the breech block near the end 30 thereof. At the 15 corner of the end 30 of the breech block 16 nearer to the kerf 60 there is an edge recess 65 running from the edge 66 of the breech block and terminating at an abrupt shoulder 67. A portion of the edge recess 65 and the 20 abrupt shoulder 67 are back of a portion of the channel 64 at the end 68. At the other corner of the end 30 of the breech block 16 there is another edge recess 69 running from the edge 70 of the breech block and terminating in a sloping shoulder 71. A portion of this edge recess 69 and the sloping shoulder 71 are back of a portion of the channel 64 at its other end 72.

Keyed in the hole 29 of the rear end 30 of the breech block 16 is the end 73 of a rod 74 having fastened upon its other end 75 the mutilated gear wheel 76 with the teeth 77 and the flat edge 78. On a pivot 79 is placed a sector-shaped hammer 80 in operative location with the gear wheel 76 and the rear of the breech block 16. This hammer 80 has a width corresponding to that of the kerf 60 and a rounded end 81 fitting the curved end 63 of the kerf 60. The hammer has at 40 one corner a pointed heel 82 at the other end and a notch 83 at the heel. Near the other corner, the hammer has a curved rack of teeth 84 and a single enlarged tooth 85 at the top end of the rack, the teeth being 45 on the side of the hammer toward the wheel 76. The single tooth 85 passes loosely through a hole 86 in the hammer 80 and is attached to the loose end 87 of a spring 88, the other end 89 of which is fastened to the 50 hammer 80. Near the lower edge 90, the hammer 80 has a pin 91 projecting sideways on the side opposite to that on which is the rod 74. On the underside of this pin 91 bears the loose upper end 92 of a flat 55 spring 93, the other and lower end 94 of which is secured to the breech 4. Hooked over the pin 91 is the curved end 95 of the vertical arm 96 of the trigger guard 97, which is pivoted at 98 at the edge of the slot 9 of the breech 4, and which has the curved horizontal arm 99, the front end 100 of which fits into the notch 10 of the breech 4. On the trigger guard pivot 98, alongside of the vertical arm 96 of the trigger guard 60 97, there is pivoted a hammer lock 101.

The vertical arm 96 of the trigger guard 97 has a horizontal bend 102 forming this arm 96 in two parts 103 and 104, the latter being in the plane of the hammer 80. The upper main portion 105 of the lock 101 is 70 alongside of the portion 104 of the trigger guard 97 and in the plane of the portion 103, and part of the lock is alongside of part of the portion 103. At this part, the lock 101 has an end 106 which is under the arm 75 96 and is turned so as to come in the path of the pointed heel 82 of the hammer 80. The lower end of the lock 101 passes through the slot 9, has the curved front edge 107 and a spring 108 presses against 80 its rear edge 109, this spring 108 being fastened at one end to the breech 4 and bearing against the edge 109 with its other end. Pivoted in the front end 110 of the trigger guard 97 is a spring pressed, locking catch 85 111, the upper end 112 of which engages a small recess 113 in the notch 10, and the lower end projects out beyond the edge of the trigger guard. In the breech 4, at the edges of the slot 9, there is pivoted at the 90 rear of the breech block 16, the trigger 114. This trigger 114 has the finger pull 115 below the breech, the toe 116 in line with the channel 64 and a heel 117 in line with the edge recesses 65 and 69.

For better operation of the device, there is secured to the barrel 2 at the recess 11, a spring 118, by its front end 119, its rear end 120 being free. Also at the rear end of the magazine, there is located a spring 121, one 100 end 122 being fastened and the curved end 123 free and extending upwardly. At the inner end of the barrel 2, there is the usual recess 124 to receive the rim of the cartridge. The lower side of the breech is made of such a thickness that where the magazine 3 joins the chamber 5, there is a recess 125 so that the inner surface of the magazine is flush with the inner surface of the bore 21 of the breech block 16.

With the parts as indicated in Figs. 1 and 2, the trigger guard 97 is released in front by pressing on the lower end of the locking catch 111 and is swung downwardly and backwardly. Through the hooked end 95 bearing on the pin 91, the hammer 80 is swung backwardly and downwardly on the pivot 79 until the pointed heel 82 is caught by the end 106 of the hammer lock 101 and the spring 93 is pressed downwardly. The trigger guard 97 is then swung upwardly and locked in front. The trigger 114 is pulled to the position shown in Fig. 1 and the hammer lock 101 is released by pressing on its lower end, the hammer 80 moving downwardly sufficiently to permit the end 106 to be disengaged from the heel 82 of the hammer 80. The spring 93 pressing on the pin 91 causes the hammer 80 to turn on its pivot 79. The tooth 85 starts the 115 120 125 130 135 140 145 150 155 160 165 170 175 180

gear wheel 76 and through the rod 74 partially rotates the breech block 16. The other teeth 84 of the hammer 80 continue this rotation. As the breech block 16 rotates 5 the heel 117 of the trigger 114 enters the recess 69 and catching at the sloping end 71 checks the movement of the parts. The breech block 16 having pushed the spring 121 back into a recess 126 which may be 10 made for the spring, the feeder spring, represented at A, will force the first cartridge into the bore 21, pushing the plunger 33 and compressing the spring 36. The feeder spring A should be of such power as to feed 15 the cartridges to the bore 21 and also compress the loader spring 36 so that the latter may perform its own function. Further action of the hammer spring 93 causes further rotation of the breech block 16 and 20 the heel of the trigger 114 riding out of the sloping end 71 of the recess 69 and upon the surface of the breech block 16, the toe 116 of the trigger 114 is pressed into the channel 64 at its end 72. The breech block 25 continues to rotate until the toe 116 of the trigger 114 reaches the other end 68 of the channel 64, when rotation is again arrested. This brings the bore 21 with the loaded cartridge in line with the gun barrel 2. The 30 loader spring 36 then forces the plunger 33 forward which shoves the loaded cartridge into the gun barrel 2, the front edge of the breech block pushing the end 120 of the spring 118 into the recess 11 and the rim 35 of the cartridge resting in the recess 124. The gun is now loaded and ready for firing. The action of the hammer 80 is suspended, a part only of the teeth 84 having engaged a part only of the teeth 77 of the wheel 76. 40 It is now perceived that action of the hammer is controlled by the trigger through the breech block 16 and not directly. To fire the gun, the trigger 114 is pulled, the toe 116 being withdrawn from the channel 64 45 and the heel 117 enters the recess 65 at the end 67. Rotation of the breech block 16 continues, and when all the teeth 84 of the hammer 80 have engaged all the teeth of the gear wheel 76, there has been a complete 50 revolution of the breech block 16, and it is in the position shown in Figs. 1 and 2. The hammer 80 falls and its front edge entering the kerf 60 drives the firing pin 55 against the cartridge and exploding the latter causes 55 the gun to fire. The recoil forces backward the empty cartridge case which shoves the spring 118 into the recess and the rim of the cartridge catches beyond the end 120 of this spring 118. The empty cartridge, 60 striking the firing pin 55 and recoil bolt 50, drives them back, the springs 58 and 54 easing the shock. The recoil bolt 50 forces the hammer 80 backward; the teeth 84 pass clear of the flat side 78 of the gear wheel 76; the single tooth 85 moves through the 65 hole 86 of the hammer 80 and, after passing the wheel 76, is shoved out into operative position by the spring 88. The spring 93 is again pressed and the heel 82 catches the hammer lock 101. When ready to again fire, 70 the action is continued with the following additional function. As there is now an empty shell in the gun, the extractor comes into action. As the movement before described takes place, the operative finger 40 75 of the extractor 38 is turned in front of the rim of the empty cartridge. When another loaded cartridge is fed into the bore 21 and the plunger 33 is pushed inward, the extractor 38 withdraws the empty shell from 80 the gun barrel 2 into the concave recess 24. As the breech block 16 is further rotated, this empty shell is ejected from the gun through the opening 6. After the firing pin 55 and the recoil bolt 50 are turned from 85 the empty shell, the springs 58 and 54 return them to operative position.

Having described my invention, what I claim is:

1. A magazine gun, provided with a breech block, for receiving cartridges, and means, separate from and mounted wholly within the breech block, and operated by the co-operative action of the magazine loading mechanism and the movement of the breech block, for transferring the cartridges to the gun barrel. 90
2. A gun provided with a rotary breech block for receiving cartridges and means separate from, secured to the breech block 100 and rotatable therewith for transferring the cartridges to the gun barrel. 105
3. A gun provided with a barrel, a magazine with a loading spring, and between the two a breech block for receiving cartridges 110 from the magazine, and means separate from and mounted wholly within the breech block and operated by the co-operative action of the magazine loading spring and the movement of the breech block, for transferring the cartridges to the gun barrel. 115
4. A gun provided with a barrel, a magazine and between the two, a rotary breech block having a receptacle for receiving cartridges from the magazine and means separate from, secured to the breech block and rotatable therewith for transferring the cartridges from the magazine to the gun barrel. 120
5. A gun provided with a barrel, a magazine and a rotary breech block between the barrel and magazine, containing a receptacle for receiving a cartridge from the magazine and means secured within the receptacle for placing such cartridge into the gun barrel. 125
6. A gun provided with a barrel, a magazine and a rotary breech block between the barrel and the magazine, containing a receptacle for receiving a cartridge from the magazine and means for placing such cartridge into 130

the gun barrel and means for ejecting an empty cartridge from the gun barrel, both such means secured to the breech block.

7. In a gun, the combination of a barrel and magazine, side by side, a rotary breech block at the ends of the barrel and the magazine the breech block being provided with a receptacle to receive a cartridge from the magazine, means for placing such cartridge into the barrel and means for ejecting an empty cartridge shell from the barrel, both such means secured to the breech block.

8. In a gun, a breech block provided with means separate from the breech block for placing a cartridge in the gun barrel, and connected with such means, other means for extracting a shell from the gun barrel, both such means within and wholly secured to the breech block.

9. A breech block provided with a receptacle for holding a loaded shell, a hammer, a firing pin and recoil bolt and a recess for receiving an empty shell.

10. A breech block provided with an exterior channel extending partially around the breech block and two edge recesses in combination with a trigger having a toe adapted to the channel and a heel adapted to the recesses and means for rotating the breech block.

11. A breech block provided with an exterior channel extending partially around the breech block and two edge recesses, one of them having a sloping shoulder, in combination with a trigger having a toe adapted to the channel and a heel adapted to the recesses and means for rotating the breech block.

12. A gun having a barrel, a magazine, a breech made with an opening at one side, a breech block located at said opening and provided with means for transferring a loaded cartridge from the magazine to the barrel and means for ejecting an empty cartridge from the barrel through the opening in the breech, both such means secured to the breech block.

13. A gun having a barrel and a magazine side by side, a breech made with an opening at one side, a rotary breech block located at said opening and provided with a receptacle to receive a loaded cartridge from the magazine, means for placing said cartridge in the barrel and means for ejecting an empty cartridge from the barrel through the opening in the breech, both such means secured to the breech block.

14. A rotary breech block having extending therefrom a rod with a gear wheel thereon in combination with a hammer having teeth for engagement with the teeth of the gear wheel.

15. A rotary breech block having extending therefrom a rod with a gear wheel thereon in combination with a hammer having

teeth for engagement with the teeth of the gear wheel, one of the teeth of the hammer being longer than the others.

16. A rotary breech block having extending therefrom a rod with a gear wheel thereon in combination with a hammer having teeth for engagement with the teeth of the gear wheel, one of the teeth of the hammer being longer than the others, and a spring which holds the latter tooth to the gear wheel.

17. The combination of a breech block having a rod extending therefrom with a mutilated gear wheel, and a hammer having teeth for engagement with the teeth of the gear wheel, one of the teeth of the hammer being longer than the others.

18. A gun having a barrel, a magazine, a rotary breech block, means for automatically feeding cartridges to the breech block and means for automatically loading cartridges from the breech block into the barrel.

19. A gun having a barrel, a magazine, a rotary breech block, means for automatically feeding cartridges to the breech block and means secured to the breech block for loading cartridges from the breech block into the barrel.

20. A gun having a barrel, a magazine, a spring within the magazine, a rotary breech block having a receptacle and a spring within the receptacle.

21. A gun provided with a barrel, and a magazine, side by side, a rotary breech block at the ends of the barrel and magazine, having a receptacle to receive cartridges from the magazine, a spring in the magazine to feed cartridges into the receptacle and another spring in the receptacle to load cartridges into the barrel.

22. A pivoted hammer having a pin extending therefrom and a pointed heel in combination with a pivoted trigger guard having a hooked end to engage the pin and a safety lock having an end to engage the pointed heel.

23. A breech block provided with a receptacle to receive cartridges and a plunger in said receptacle and an extractor connected with such plunger.

24. A breech block provided with a receptacle to receive loaded cartridges from a magazine and a recess to receive empty cartridges from the gun barrel and having in the receptacle a plunger and connected with such plunger an extractor, the operative finger of which extends into the recess.

25. A breech block having two passages therethrough and in one passage a firing pin and in the other a recoil bolt.

26. A breech block having two passages therethrough and in one passage a firing pin and in the other a recoil bolt, each having a collar and a spring on each side of the collar.

27. A breech block having two passages

running lengthwise therethrough, one oblique and the other parallel to the axis of the block, and in the former a firing pin and in the latter a recoil bolt, the block also having at its front end a recess into which the front ends of the firing pin and the recoil bolt extend.

In testimony whereof I have affixed my signature in presence of two witnesses.

KIRBY FITZPATRICK.
